Fig. 3.

Fig. 2.

Fig. 1.

FIG. 1 is a perspective view of a combined cover and utensil holder for a cooking dish or the like showing my new design in association with a typical cooking dish assembly shown in broken lines for illustrative purposes;

FIG. 2 is a slightly enlarged scale side elevational view thereof; and

FIG. 3 is a top plan of the cover.

I claim:

The ornamental design for a combined cover and utensil holder for a cooking dish or the like, substantially as shown and described.
